GRINDER AND SHARPENER ATTACHMENT
FOR MEAT GRINDERS

Andrew J. Kirkland, West Palm Beach, Fla.

Application December 14, 1936, Serial No. 115,826

4 Claims. (Cl. 51—241)

5 My invention relates to knife grinding and sharpening means, and more particularly to a device which may be readily attached to the motor of a meat grinder, and it consists in the constructions, arrangements and combinations herein described and claimed.

It is an object of the invention to provide an attachment embodying a shaft having mounted thereon the necessary grinding and sharpening 10 disks, as well as buffer disk, the shaft being constructed for quick and rigid attachment to the drive shaft of the motor.

It is also an object of the invention to provide an adjustable pedestal support for the shaft of 15 the attachment, permitting its ready adjustment to various constructions of meat choppers or grinders.

It is a further object of the invention to provide a separable shaft, each section including 20 one or more grinding or buffing elements, thereby making it possible to employ a single grinding element, if desired, or the entire number of elements may be rotated as a unit.

It is a still further object of the invention to 25 provide a pedestal support having means attachable to one end of the grinder shaft and permitting swinging movement of the shaft to a position clear of the driving motor.

Additional objects, advantages and features of 30 invention will be apparent from the following description considered in conjunction with the accompanying drawing, wherein

Figure 1 is a side elevation of my invention as installed upon a meat chopper or grinder.

35 Figure 2 is a similar view showing a single emery wheel associated with the driving motor, and also showing the position of the other emery wheel and buffer when not in use.

Figure 3 is a fragmentary perspective view 40 illustrating the in-operative positions of one of the emery wheels and buffer.

Figure 4 is a fragmentary sectional view of the pedestal and bearing for the shaft.

Figure 5 is an enlarged sectional view illustrating the bearing and shaft connection at the driving motor.

50 There is illustrated a base 10 which may be of any approved construction, at one end of which there is suitably mounted an electric motor 11, employed ordinarily for driving a meat chopper or grinder (not shown). The motor 11 includes a driven shaft 12 suitably journaled as at 13 in a boss 14 of the motor casing. The shaft 12 stops short of the outer end of the boss and includes a transversely extended slot 15, receiving

5 a tongue 16 of a grinder shaft 17. The boss 14 as now constructed, has an annular recess 18, concentric with the shaft 12 and receives therein a bushing 19 of the shaft 17, as will now be fully described.

The shaft 17 and shaft 17' constitute the mounting means for the grinding disks, buffers, etc., the shafts being arranged in end to end relation, one end of the shaft 17 being journaled in the boss 14 while the opposite end of the shaft 10 17' is journaled in an adjustable pedestal 20.

The shaft 17 has a pair of spaced washers 21 and 22, fixed thereto and interposed between these washers there is a sleeve bearing 23, the latter being journaled in the bushing 19. The 15 bushing 19 snugly fits within the recess 18 and is locked therein by a set screw 24. Obviously, the mounting of the shaft 17 so as to mate the slot 15 and tongue 16, rotation of the motor shaft 12 will cause rotation of the shaft 17 and its 20 associated grinding disk 25. The outer end of the shaft 17 terminates in a tongue 26 adapted to interfit with a slot 27 formed in the end of the shaft 17', and preferably a sleeve 28 is disposed around the juncture of the shafts to maintain 25 alignment and engagement of the slot and tongue.

The outer end of the shaft 17' is revolvably mounted in a bushing 29 journaled in a collar 30, the latter being fixed to a yoke 31 of the 30 pedestal 20. The yoke 31 includes a pair of up-standing arms 32, each of which has a threaded aperture and receiving respective adjusting screws 33. The screws 33 engage in suitable countersunk bearings formed in the periphery of 35 the collar, and as may be clearly seen in Figure 4, are in opposed relation. Thus, the shaft 17' may be laterally adjusted by manipulation of the screws and locked in such position upon tightening of the lock nuts 34. This adjustment 40 may be necessary in adapting the grinder attachment to certain makes of meat choppers, and in addition, the yoke 31 may be vertically adjustable, and this by reason of the fact that the stem 35 thereof may be moved upwardly and 45 downwardly through the socket 36 of the pedestal. The stem 35 may be locked in adjusted positions by means of the screw 37, threadedly engaged in a boss 38 and impinging the stem.

The shaft 17' has secured thereon a buffer 39 50 and grinding disk 40 suitably spaced along the length of the shaft.

The use of the attachment will be readily understood from the following description. The meat chopper ordinarily associated with the mo- 55

tor 11 will be removed, exposing the recess 18 and shaft 12, and the collar and sleeve bearing 19—23 of the shaft 17 inserted therein, the tongue 16 entering the slot 15. The set screw 24 is now 5 tightened, locking the bushing 19 within the recess. Thus with operation of the motor, the shaft 17 will be driven, rotating the grinding disk 25. This position may be readily seen from consideration of Figure 2, and it will also be seen that the 10 shaft 17' and associated buffer and grinding disk has been swung upon the adjusting pins 33 so as to clear the disk 25, the shaft 17' resting upon an upright support 41 carried upon one of the base 18. The grinding disk 25 may thus be used 15 for sharpening knives and tools of various kinds, and should a buffer or further grinding be required the motor will be stopped and the shaft 17' then swung upon the adjusting pins 33 so that the shafts 17 and 17' are in alignment allowing interlocking engagement between the 20 tongue 26 and slot 27. Should it become necessary to center the shaft 17' with the shaft 17, this may be accomplished by manipulation of the adjusting screws 33 to effect a lateral movement of the shaft in one direction or the other, and if a vertical adjustment is required, this may be effected by loosening the lock screw 37 to 25 release the stem 35. The yoke 31 may then be raised or lowered, as desired, and secured by 30 tightening the lock screw 37.

From the foregoing it will be apparent that I have provided a grinding attachment which may be quickly installed in place of a meat chopper, and by providing separable shafting, a single 35 grinding disk may be employed, or several disks and buffers may be utilized, permitting several grinding or polishing operations, as may be required in some instances.

While I have shown and described a certain preferred construction, this is by way of illustration 40 only, for I am aware that changes may be made, and I therefore consider as my own, all such modifications in structure as fairly fall within the scope of the appended claims.

45 I claim:—

1. A grinder attachment for meat choppers and the like comprising in combination, a motor having a shaft and an open ended boss circumscribing the shaft, said shaft having a transverse slot 50 across the end thereof, a grinder shaft having a

bearing complemental to the boss and removably fixed therein, a bearing in the first named bearing and revolvably supporting the grinder shaft, a tongue on the grinder shaft engaged within the transverse slot of the motor shaft, a grinder disk on the grinding shaft, said last named shaft having a transverse tongue at the end thereof, a buffer and grinder shaft arranged in end to end relation with the grinder shaft and having a slot receiving the tongue, buffer and grinder disks on the buffer and a grinder shaft, and adjustable support means for the outer end of the last named shaft. 5

10 2. The structure of claim 1 wherein the support means is vertically and laterally adjustable. 15

20 3. A grinder attachment for meat choppers and the like comprising in combination, a motor having a shaft and an open ended boss circumscribing the shaft, said shaft having a transverse slot across the end thereof, a grinder shaft having a bearing complemental to the boss and removably fixed therein, a bearing in the first named bearing and revolvably supporting the grinder shaft, a tongue on the grinder shaft engaged within the transverse slot of the motor shaft, a grinder disk on the grinding shaft, said last named shaft having a transverse tongue at the end thereof, a buffer and grinder shaft arranged in end to end relation with the grinder shaft and having a slot receiving the tongue, buffer and grinder disks on the buffer and a grinder shaft, and adjustable support means for the outer end of the last named shaft. 25 30

35 4. A grinder attachment for meat grinders and the like comprising in combination, a motor having a shaft, a second shaft, detachable coupling means between the shafts for end to end connection, a grinding disk on the motor shaft, a buffer and grinding disk on the second named shaft, an adjustable support means for the second named shaft, said last named shaft having pivotal connection with the support means whereby said 40 shaft may be swung to a position clear of the motor shaft upon uncoupling of the shafts and a support for the second named shaft when in the latter position. 45
